WATER SERVICE DEVICE

James W. McGarry and Howard A. Eads, Cincinnati, Ohio, assignors to Railroad Products Company, Cincinnati, Ohio, a corporation of Ohio

Application February 1, 1946, Serial No. 644,687

7 Claims. (Cl. 137—13)

1

This invention relates to a water service device or hydrant for the delivery of potable water from a main or other source of water under pressure.

An object of the invention is to provide an improved water service device which is self-draining and therefore protected against freezing, and incorporating means to render it free of back-siphonage and the possibility of pollution.

Another object is to provide improvements in a water service device having the foregoing features, including structure to protect the device from all outside sources of contamination.

Another object is to provide such a device with simple and reliable means for visually indicating the operating condition thereof at all times.

A further object is to provide a device of the character stated, which is fully automatic and substantially free of maintenance expense and servicing difficulties, the mechanism thereof being arranged for easy access, however, in the replacement or repair of wearing parts.

Another object is to provide simple means for the selective transfer of waste water to either a sewer or a drainage pit, as may be desired.

A further object is to simplify the mechanism and reduce the cost of production of a device embracing all of the advantages and meritorious features aforesaid.

The foregoing and other objects are attained by the means described herein and illustrated in the accompanying drawings, in which:

Fig. 1 is a side elevational view, partly in cross section, showing the improved water service device of the invention.

Fig. 2 is an enlarged cross-sectional view of an ejector mechanism constituting a detail of the invention.

Fig. 3 is an elevational view of an ejector control valve stem.

Fig. 4 is an enlarged perspective view of an ejector control valve actuator.

Fig. 5 is a fragmental elevational view, partly in cross section, showing a platform of flush type hydrant which might be substituted for the pedestal hydrant illustrated in Fig. 1.

Fig. 6 is a view similar to Fig. 5, showing a modification of the platform or flush type hydrant.

Fig. 7 is a fragmental side elevational view of the hydrant housing illustrated by Fig. 1.

Fig. 8 is a fragmental cross-section taken on line 8—8 of Fig. 7.

Water service hydrants frequently are installed in locations where sewer or drainage conditions are poor, and where poor drainage or flat ter-

2

rain result in contaminated water accumulating and standing about the hydrant. Such conditions present a problem of contamination or pollution of potable water supply lines connected

5 with the hydrant, through back-siphonage or other conditions prevailing to contaminate the interior of the hydrant and the water supply line connected thereto. Many different types of hydrant structures have been proposed in the ef-

10 fort to overcome problems of potable water supply line pollution resulting from the conditions mentioned above, or from conditions of a similar nature, but in the past such structures have proven objectionable due to their complexity and

15 the cost of maintaining them in an operating condition. One of the primary objects of the present invention is to produce a simple, fully automatic, and highly serviceable hydrant structure which will protect the potable water supply

20 line under all adverse conditions encountered at the site of installation. Other desirable features of the device have been previously set forth in the objects previously specified, and others may become manifest as the description proceeds.

25 Referring to Fig. 1 of the drawing 12 indicates the housing of a pedestal type hydrant which stands above the ground line or platform level indicated at 13. Beneath the line 13 is a reservoir assembly indicated generally by the character 14, and which includes certain operating mechanism disposed at a proper depth to avoid the possibility of freezing during the winter season.

A potable water supply line delivering water to the hydrant structure is indicated at 15. The supply line feeds a pipe section 16 which enters

30 a T-fitting 17, which in turn is connected to a valve body 18 containing a longitudinally slideable valve head 19, the valve head being normally held against a valve seat 20 to prevent a flow of water upwardly through the hydrant structure. The

35 valve body 18 may be substantially of conventional design, and will include a drain port 21 which is uncovered when the valve is seated, so that water may not stand and freeze within the riser 22 which conveys water to the hydrant nozzle or

40 outlet 23 subsequently to opening and closing movements of the main valve 19. As will be understood, drain port 21 is covered and closed by valve head 19 whenever the valve head is lifted

45 from its seat 20 to initiate a flow of water to the hydrant nozzle.

The main valve head 19 may be vertically actuated in any suitable manner, and with the use of conventional means if desired. For the purposes of the present explanation, the valve head

is fixed to the lower end of a valve stem 24; the upper end 25 carries a stem head 26 surrounded by a compression spring 27 which acts constantly upon a flange 28 of part 26, to yieldingly maintain a seated condition of the main valve. The reciprocating part 26 may carry at its upper end a pivot 29 on which is mounted an actuating handle 30, said handle including a cam face 31 to engage the top of the hydrant cap 32 upon elevating and rotating the handle upon pivot 29. As the handle is moved toward an upright position, the toe of the cam bears upon the hydrant cap and draws the valve stem upwardly to unseat the main valve and establish a flow of water through the hydrant nozzle 23. At 33 is indicated a suitable packing arrangement for preventing leakage along the valve stem part 26. The hydrant cap may be detachably secured to the stock or head of the hydrant indicated at 34.

The housing of the hydrant may include a casing 35 for the riser tube 22, and may be capped by a casing plug of rubber or other suitable material, as indicated at 36. The riser casing is otherwise unsupported by the hydrant housing, as will be explained hereafter.

The base of the hydrant housing is enlarged to provide a hollowed dome 37 which serves as a protective cover for the upper portion of the buried reservoir assembly 14. The housing 12 including dome portion 37 may be in two parts, or of split construction, opposite halves thereof being fastened together by means of suitable bolts or screws 38 projecting therethrough. The base of the housing may rest upon any surface indicated by the line 13.

The opposed halves of the dome portion 37 of the housing are depressed inwardly to provide a recess as indicated at 39 of Fig. 7, said recess having an exposed upper wall 40 and a similar lower wall 41 located directly beneath it, both of said walls being provided with vertically aligned apertures 42 and 43. These apertures in the recess walls constitute means for visually indicating the operating condition of the faucet mechanism, as in the normal operation of the device there will be evident at intervals, a stream of waste water passing from opening 42 to opening 43, the stream being observable exteriorly of the hydrant housing due to the exposed character of the openings. The stream of water mentioned emanates from the waste water spout 44, and is projected through the openings 42 and 43 by the spout as the waste water is supplied to the latter at periodic waste water displacement cycles occurring within the reservoir. Waste water discharged from spout 44 through the openings 42 and 43, enters the open upper end of a pipe or tube 45 located beneath the wall 41 of recess 39. By means of pipe 45, the waste water may be carried away from the vicinity of the hydrant.

As was stated above, a visual waste flow indicator of the character illustrated by Fig. 7, is duplicated at opposite sides of the hydrant housing. One of said indicators may include the waste pipe 45, and the other may include a similar waste pipe, so that two waste pipes are provided, one at each side of the housing. One waste pipe may be connected to a sewer, and the other may be connected to any other waste water disposal means, for example a drainage pit or gravel bed such as is commonly used for drainage water disposal purposes. Waste water from the instant service device may be directed selectively to a pipe such as 45 connected with the sewer, or to a

similar pipe at the opposite side of the housing, connected with a drainage pit or the like, by simply swinging the spout 44 on its vertical axis until the opening of the spout registers with an opening such as 42 of the waste flow indicator means. From the foregoing, it will be understood that spout 44 may be swung through a limited arc at its threaded connection 46, shown in Fig. 1. The single swingable spout 44, and the recesses 39 at opposite sides of the dome 37, constitute alternative waste flow indicators which may be seen by an attendant as he walks past the hydrant in the performance of his regular duties. Should the attendant observe that no waste water flows through the visual indicator at intervals, he will know that the water service device is not operating properly, and the fact may then be reported to the maintenance man. It is to be understood, of course, that only one of the waste flow indicators will be in operation in any particular installation. If the waste water is directed to a sewer, one indicator will be used, whereas if the waste water is directed to a drainage pit, the other indicator will be used, the use being selective by reason of the swinging of spout 44 toward one side or the other of the housing dome 37.

Attention is now directed to the operating mechanism which is below ground level and housed within the reservoir 14. It may first be noted that reservoir 14, in the preferred construction, will comprise a pair of upright cylindrical tanks 47 and 48, said tanks providing adjacent chambers 49 and 50 which are placed in fluid communicative relationship by means of a nipple 51 located near the bottom walls 52 and 53 of the cylindrical tanks. Along a line 54 where the side walls of the tanks abut one another, the tank walls may be welded or otherwise fixedly secured together to furnish a unitary reservoir structure. It may here be noted that the nipple 51 passes through the walls of both tanks, and will preferably be welded thereto in a manner such as to avoid leakage of water from the inside of the tanks to the earth, or vice versa. The bottoms of the tanks are carefully applied and welded in place, likewise for the purpose of precluding contamination of the chambers 49 and 50 from outside sources. To tightly seal the tanks at their upper ends, each may be provided with a tightly fitted annular bushing member 55 threaded interiorly to detachably mount the leak-proof caps 56 and 57. To obtain a tight connection at the cap threads, the threads will desirably be tapered in the manner of pipe fitting threads. The riser tube casing 35 is applied to reservoir cap 57 at the tight threaded connection 58, and is closed at its upper end by means of the casing plug 36 to prevent entry of foreign substances into the reservoir chambers. As will be understood, the waste pipe 45 is located exteriorly of the tanks 47 and 48, so that no contamination is risked at that location. From the foregoing it will be understood that the reservoir chambers are thoroughly protected from contamination from outside sources. The fitting 59 at the potable water supply line is leak-proof, of course.

Tank 47 contains the potable water supply line, the faucet control valve 18, and the riser 22. This tank receives all water drained through the port 21 from riser 22, at each closing movement of the main valve. This drain water, of course, is potable and as clean as the water of the supply line. After every closing movement of the main valve, a quantity of water equal to the capacity of riser

22 enters tank 47 through the drain port 21, as this port is open whenever the main valve is closed. The drainage water is permitted to enter the tank 48 through the connecting nipple 51, displacing air at the slip-joint 64, so that the water level in both tanks will always be equalized.

Tank 48 constitutes a float chamber and a compartment in which is disposed a drain water ejector indicated generally by the character 60. The ejector is so associated with the float 61 as to go into action for displacing drainage water from the tank chambers before the level of drainage water reaches the elevation of the ejector and the main valve 18. Drainage water displaced by the ejector is conveyed from the open lower end of a suction pipe 62 through the ejector discharge pipe 63, the upper end 64 of which is in fluid communicating relationship with the swingable spout 44 of the waste flow indicator. From the general description above given, it may readily be understood that the operation of the ejector is controlled by float 61, so that whenever the waste water from port 21 reaches a predetermined level in the chambers 49 and 50, the ejector will be placed in operation to substantially empty the chambers of waste water.

With particular reference to the ejector, it may be noted that this element is associated with a housing 59 having an inlet chamber 65 connected to the supply of water under pressure by means of the tube or extension 66 of the T-fitting 17. Tube 66 has a threaded connection with a fitting 67 that extends through the tank walls, and this fitting in turn is provided with a fixed upstanding nipple 68 disposed within the float chamber. Nipple 68 is extended vertically within the chamber, and has a smooth upper end 69, preferably tapered and reduced, so that it may enter a gland nut 70 of the ejector control inlet, the nipple having a slip fit within the nut and within a gasket 71 held in place by said nut. The slip joint between the nipple 68 and the ejector inlet should be reasonably leak-proof, although any small amount of leakage at the joint will not defeat the anti-pollution characteristic of the device.

Flow of water under pressure from the supply line may not normally occur through the ejector, because of the normally seated condition of the pilot valve 72 closing off the ejector control inlet chamber 65 from the outlet chamber 73 thereof. This pilot valve, however, is to be unseated by the action of float 61 when elevated to a predetermined extent by an accumulation of drained water within the reservoir chambers. Whenever the pilot valve 72 is unseated, water under pressure from the supply line will pass through the ejector control housing 59, entering the ejector 60 through the pipe connection 74. The ejector may be of standard design, and will include a nozzle or jet 75 delivering water under pressure to the venturi 76, which creates a vacuum in chamber 77 to lift drained water from the float chamber through the suction pipe 62. The discharge from the jet and from the suction pipe 62 leaves the reservoir through tubes 63 and 44, this action being common and well known in the operation of all types of ejectors. The ejector will remain in operation as long as the pilot valve 72 is held open by the action of float 61. As the float reaches its lower limit of travel, however, it will permit closing of the ejector control or pilot valve 72, thereby terminating the action of the ejector so that drained water from the hydrant riser 22 may again ac-

cumulate within the reservoir to eventually initiate the drain water ejecting cycle.

The float control for the ejector control valve 72 may consist of an upright link 78 pivoted as at 79 to the top of the float. Link 78 is provided with an elongated slot 80 which slidably accommodates a pin 81 carried by the forked end 82 of a cam lever 83 disposed above the float. To the lever 83 is fixedly applied a cam 84 which at 85 is pivotally mounted upon a bracket 86 extending from the housing 59 of the ejector control valve. A finger 87 on the cam extends upwardly for reception in an opening or socket 88 provided by a head 89 fixed to the outer end of pilot valve stem 90. Accordingly, as the cam is rocked about its pivot 85, the finger 87 will act upon valve stem head 89 to reciprocate stem 90 to open and closed valve positions. Valve stem 90 may be packed to preclude leakage, as indicated at 91.

The edge of cam 84 preferably is provided with a pair of notches 92 and 93 in which may seat alternatively the head 94 of a leaf spring 95, the latter having its base end 96 fastened to the ejector control valve housing at the location 97. In the lowered position of float 61, the head of the leaf spring engages the lower notch 93, and this engagement persists until the float elevates sufficiently to bring the abutment 98 of link slot 80 into firm contact with the pin 81 of the cam lever. When the upward force imposed upon the cam lever by the buoyancy of the float reaches a sufficient value to displace the spring head 94 from cam notch 93, the cam will be rotated about its pivotal mounting 85 sufficiently to place the upper notch 92 in engagement with the spring head. Concurrently with this action of the cam, finger 87 will shift the valve stem 90 for opening the ejector control valve 72, whereupon the ejector will be placed in operation to immediately begin to perform its function of displacing drained water from the reservoir and thereby lowering the water level. As the water level is lowered, the float 61 moves freely downwardly a distance corresponding to the length of link slot 80, until the upper end 99 of the link slot engages the cam lever pin 81. Because of the restraining action of spring head 94 then engaged in the upper notch 92 of the cam, the cam will not immediately be rocked to close the ejector control valve, but instead, the closing movement will be delayed until the weight of the float is in effect sufficiently increased by the continued lowering of the water level in the reservoir, to overcome the restraining action of the leaf spring head 94 upon the cam. It will therefore be understood that the displacement of practically all the water from the reservoir will permit the full weight of the float to act upon the spring 95 to dislodge it from the upper cam notch 92, thereby returning the parts to the normal operating condition of the water service device, at which the ejector control valve 72 is closed. Adjustments of the force of spring 95 necessary to produce the desired reaction upon the cam, may be effected in any suitable manner, as by varying the thickness of a shim 100 which supports the base end of the spring.

Referring further to the float 61, it is to be noted that this element comprises a buoyant cylindrical can, preferably with a top wall 101 which is centrally apertured to support a longitudinal sleeve 102 serving as a guide for the float in its vertical movements along the suction pipe

62. The bottom wall 103 of the float likewise is apertured at its center and supports the lower end 104 of sleeve 102. The lower end 104 of the sleeve depends beneath the plane of the bottom wall 104, and with the lower annular edge 105 of the float body, forms an air trap chamber 106 directly beneath the bottom of the float. Under this arrangement, it will be understood a rising level of water within the reservoir will begin to buoy the float as soon as the water reaches the lower end of sleeve 102, and that further elevating of the water level will result in an entrapment of air within the space directly beneath the bottom wall 103 of the float. As the float approaches its upper limit of travel and meets resistance imposed by spring 95, the entrapped air beneath the float is compressed to a certain limit, until the spring finally yields, and the suppressed buoyancy of the float augmented by the stored force of the entrapped air, thereupon acts to vibrate or jiggle the float with sufficient force to overcome any tendency of the pilot valve stem, the float linkage, its pivots, to stick or bind. Again, upon descent of the float as the water level reaches its lower limit within the reservoir, a suction will be created beneath the float resulting in a vibratory movement for the same purpose. By means of this construction, the operating parts of the float mechanism are kept in a freely operating condition with every cycle of operation of the device, so that maintenance and servicing due to corrosion and the like are reduced to a minimum. The character 106 indicates an opening near the lower end of the suction pipe 62, through which the drainage water flows into the pipe during the operating period of the ejector. As will be understood, the suction pipe 62 may be used as a guide for the float; however, the float obviously may be guided by other means, if desired.

Figs. 5 and 6 of the drawings are presented for the purpose of illustrating how the device of Fig. 1 may be converted from a pedestal type hydrant, to a hydrant of the flush type sometimes referred to as platform type of hydrant. As is obvious, the housing 12 from the ground line 13 upwardly, may be lifted bodily from that portion of the device which is buried in the earth. The pedestal or housing 12, when displaced, exposes the reservoir caps 56 and 57 which may be then covered by the structures illustrated by Figs. 5 and 6. In these drawing figures, the same caps and tanks as are illustrated by Fig. 1, are shown. In accordance with Fig. 5, the riser 22 has been shortened and at its upper end there is applied a fitting 107 corresponding to the hydrant stock of Fig. 1, differing therefrom in that it is more squatly in design and having a threaded outlet indicated at 108. The operating handle 109 may be similar to that of Fig. 1, and may operate in the manner previously explained for lifting the main valve rod to permit a flow of potable water to the outlet 108. The outlet may be furnished with a suitable nipple 110 to which may be fixed one end 112 of a flexible hose or the like 113, the opposite end 114 of which is fixed to a coupler 115. Coupler 115 is fixedly secured, as by means of screws or bolts 116, to the inside face of a flush lid 117 which may be hinged to the sunken box 118, as indicated at 119.

From the foregoing, it will be understood that swinging the lid to the open position about its hinge mounting 119, will bring the coupler 115 into convenient position for the attachment of a complementary coupler, the latter being usually

fixed to one end of a rubber hose or the like used for flushing purposes, or for filling tanks or other receptacles with potable water. When such hose is not in use, it may be detached from coupler 115, whereupon the lid 117 may be closed upon the rim 120 of the box 118.

At the location 121, the bottom 122 of box 118 may be apertured to accommodate the waste water pipe 45 previously mentioned in connection with Fig. 1, and into this pipe may be discharged the waste water ejected through the swing spout 44. With the hydrant stock 107 securely mounted upon the cap 57 at the location 123, all of the mechanism enclosed by means of the caps 56 and 57 is protected against contamination from any substances that might enter the service box 118. The box may be furnished with a side outlet 124 if desired, to ensure drainage of polluted water that might seep into the box about the rim 120; however, the box rim will preferably be elevated somewhat above the ground line 13 to avoid entry of water-borne foreign substances.

A preferred form of water service box is illustrated by Fig. 6, wherein the hydrant stock and its associated mechanism are indicated generally by the character 125. In this instance, the outlet 126 is fixedly attached to one end 127 of a flexible hose or the like 128, the opposite end 129 of which is located above the level of the box rim 130. A coupler 131, similar to the coupler 115 of Fig. 5, is fixed at 132 to the inside of a crown lid 133 which is considerably above the box rim 130. It will be seen by referring to Fig. 6, that the water service box 134 may be filled with contaminated water to the height of its rim, without subjecting the inlet 135 of the coupler to contamination or pollution. The lid 133 may be hinged to the service box at 136, and as evident, the coupler 131 moves with the lid when swung to the open position, by reason of the flexibility of hose 128. The service box of Fig. 6 may be equipped to accommodate a sewer pipe such as 45, if desired, while under certain circumstances the swing spout 44 may be permitted to discharge directly into the service box, the latter being furnished with a drain pipe 137 leading to any convenient depository for the waste water ejected from the reservoir comprising tanks 47 and 48. The manner in which waste water is led from the service boxes of Figs. 5 and 6, is a matter relatively unimportant to the invention. It should readily be evident, however, that flush boxes of a type illustrated by Figs. 5 and 6 can be substituted for the pedestal hydrant of Fig. 1 without difficulty, while at the same time retaining all of the advantages inherent in the pedestal hydrant as previously noted.

The air gap between the ejector discharge spout 44 and the drain pipe, is in each instance made sufficiently extensive to avoid all possibility of back-siphonage that might introduce polluted water or contaminating substances into the potable water supply line. Whenever it is possible to do so, the spout 44 is placed at an elevation above the ground line 13, or such other surface as might support a stand of extraneous impure water.

In the event that any wearing parts of the apparatus within the buried reservoir should require replacement or repair, such parts are rendered easily accessible by reason of the fact that the pedestal housing may readily be lifted from covering relationship to the reservoir caps 56 and 57. In the case of the main valve 19, it is

necessary only to detach the hydrant stock and lift the valve stem vertically upwardly from its position within the valve housing 48. Valves may quickly and easily be replaced in this manner. Should it be necessary to have access to the float and ejector mechanisms, it is necessary only to remove the hydrant housing 42, whereupon the reservoir cap 56 may be unscrewed from the bushing 55 and bodily removed to open the upper end of the tank, so that the complete unit consisting of the float 61, suction pipe 62, ejector 60, housing 59, and discharge pipe 63, may be bodily lifted out of the tank, this operation being permitted and facilitated by reason of the slip joint provided at the nipple 68. The connection between the cap 56 and the upper end 64 of the ejector discharge pipe 63 likewise is a slip joint, which involves no interference with bodily removal of cap 56. After the float and ejector unit has been bodily lifted from tank 48, repairs or replacements may be made thereon, or as an alternative, a complete replacement unit may be substituted therefor. It will accordingly be understood that maintenance costs may be reduced to a minimum in a device constructed as disclosed herein.

In the case of the flush boxes, access to the reservoir caps 56 and the mechanism beneath it, may be had by simply removing or displacing the flexible hoses 113 or 128, whereas main valve replacements are usually effected by removing the hydrant head or stock and pulling the main valve and stem from the riser.

Various modifications and changes in the details of construction may be resorted to, within the scope of the following claims. For example, the actuating mechanism for the pilot valve might be altered in form, and the float may be guided otherwise than by means of a suction pipe 62. The particular type of ejector 60 employed in the combination is a matter of immateriality to the invention, since many forms of ejectors are available for use in the combination. Likewise, many forms of main valves 18-19 are available for use in the device, and actuating means therefor need not necessarily be of the type illustrated at the upper end of the hydrant stock. The buried reservoir will, of course, be constructed of materials capable of withstanding the destructive effects of oxidation and chemical reactions which usually take place in the earth.

What is claimed is:

1. A device of the class described, comprising in combination, a hydrant having an outlet for the delivery of water, an upright riser tube having connection with a source of water under pressure near its lower end, and with the hydrant outlet near its upper end, a main valve in the riser and means for opening and closing said valve, the valve including a port to drain the riser upon each closing movement of the valve, an upright elongated tank for embedment in the earth and enclosing the main valve and a portion of the riser, said tank including a displaceable sealing upper cap, a second upright tank substantially coextensive with the first, and including means placing the tanks in fluid communication near lower ends, a displaceable upper cap sealing the second tank, a water pressure connection extending from the source of supply and terminating in the second tank, and a bodily displaceable float-operated ejector assembly in the second tank having a slip-joint connection with the terminus of the water pressure connection, whereby said assembly is rendered instantly

displaceable from the second tank as a unit, upon removal of the cap of said second tank.

2. A device of the class described, comprising in combination, a hydrant having an outlet for the delivery of water, an upright riser tube having connection with a source of water under pressure near its lower end, and with the hydrant outlet near its upper end, a main valve in the riser and means for opening and closing said valve, the valve including a port to drain the riser upon each closing movement of the valve, an upright elongated tank for embedment in the earth and enclosing the main valve and a portion of the riser, said tank including a displaceable sealing upper cap, a second upright tank substantially coextensive with the first, and including means placing the tanks in fluid communication near their lower ends, a displaceable upper cap sealing the second tank, a water pressure connection extending from the source of supply and terminating in the second tank, and a bodily displaceable float-operated ejector assembly in the second tank having a slip-joint connection, whereby said assembly is rendered instantly displaceable from the second tank as a unit, upon removal of the cap of said second tank, and means above the tank caps for visually indicating exteriorly of the hydrant, the flow of drained water displaced from the tanks by operation of the ejector assembly.

3. A device of the class described, comprising in combination, a hydrant having an outlet for the delivery of water, an upright riser tube having connection with a source of water under pressure near its lower end, and with the hydrant outlet near its upper end, a main valve in the riser and means for opening and closing said valve, the valve including a port to drain the riser upon each closing movement of the valve, an earth embedded reservoir receiving and accumulating the drained water from said port, said reservoir including a discharge pipe extending to the exterior of the reservoir, and a down-turned spout communicating with said discharge pipe, to direct the drained water downwardly outside the reservoir, and an exterior waste receptacle, the spout being spaced from the receptacle to provide an air gap, avoiding back-siphonage.

4. A device of the class described, comprising in combination, a hydrant having an outlet for the delivery of water, an upright riser tube having connection with a source of water under pressure near its lower end, and with the hydrant outlet near its upper end, a main valve in the riser and means for opening and closing said valve, the valve including a port to drain the riser upon each closing movement of the valve, an earth embedded reservoir receiving and accumulating the drained water from said port, a discharge pipe extending from the interior to the exterior of the reservoir, a hollow base for the hydrant having a recess therein with spaced upper and lower apertured walls, the apertures of said walls being exposed exteriorly of the base and vertically aligned, a waste receptacle directly beneath the lower wall aperture, and a down-turned spout in the hollow base communicating with said discharge pipe and overhanging the aperture of the upper wall of the recess in spaced relationship, to direct a stream of discharged water through both of the aligned apertures and into the waste receptacle beneath them.

5. A device of the class described, comprising in combination, a hydrant having an outlet for the delivery of water, an upright riser tube hav-

ing connection with a source of water under pressure near its lower end, and with the hydrant outlet near its upper end, a main valve in the riser and means for opening and closing said valve, the valve including a port to drain the riser upon each closing movement of the valve, an earth embedded reservoir receiving and accumulating the water from said port, said reservoir including a discharge pipe extending to the exterior of the reservoir, a hollow base for the hydrant having a recess therein with spaced upper and lower apertured walls, the apertures of said walls being exposed exteriorly of the base and vertically aligned, a waste receptacle directly beneath the lower wall aperture, a down-turned spout in the hollow base communicating with said discharge pipe and overhanging the aperture of the upper wall of the recess in spaced relationship, to direct a stream of discharged water through both of the aligned apertures and into the waste receptacle beneath them, and means mounting the down-turned spout for swinging movement out of alignment with said apertures.

6. A platform type of water service device comprising in combination, a drainable box for embedding beneath a surface, said box having a bottom wall and a circumferential rim for disposition near said surface, a lid hinged for swinging movement upon the box to open and closed positions, a hydrant stock within the box and normally concealed by the lid, said hydrant stock having an outlet within the box, a hose coupler fixed to the box lid, and a flexible conduit for the delivery of water from the hydrant outlet to the hose coupler, an upright riser tube having connection with a source of water near its lower end, and with the hydrant outlet near its upper end, a main valve in the riser, means in the box for opening and closing said valve, the valve including a port to drain the riser upon each closing movement of the valve, an earth embedded reservoir receiving and accumulating the drained water from said port, and means operative when the drained water reaches a predetermined level in the reservoir, for substantially emptying the reservoir.

7. A platform type of water service device com-

prising in combination, a drainable box for embedding beneath a surface, said box having a bottom wall and a circumferential rim for disposition near said surface, a lid hinged for swinging movement upon the box to open and closed positions, a hydrant stock within the box and normally concealed by the lid, said hydrant stock having an outlet within the box, a hose coupler fixed to the box lid, and a flexible conduit for the delivery of water from the hydrant outlet to the hose coupler, an upright riser tube having connection with a source of water near its lower end, and with the hydrant outlet near its upper end, a main valve in the riser, means in the box for opening and closing said valve, the valve including a port to drain the riser upon each closing movement of the valve, an earth embedded reservoir receiving and accumulating the drained water from said port, means operative when the drained water reaches a predetermined level in the reservoir, for substantially emptying the reservoir, the means last mentioned including a discharge pipe extending to the exterior of the reservoir and terminating within the drainable box above the level of its bottom wall.
